UNITED STATES PATENT OFFICE.

FRANK O. E. STONE, OF AKRON, OHIO.

METHOD OF VULCANIZING RUBBER.

1,368,071.

Specification of Letters Patent.

Patented Feb. 8, 1921.

Application filed April 30, 1920. Serial No. 377,765.

To all whom it may concern:

Be it known that I, FRANK O. E. STONE, a citizen of the United States, residing at Akron, in the county of Summit and State of Ohio, have invented new and useful Improvements in Methods of Vulcanizing Rubber, of which the following is a specification.

This invention relates to a new, novel and improved method of vulcanizing or curing rubber or similar substance.

Objects of the invention are to provide a method for vulcanizing rubber which will require only simple and inexpensive equipment and which in use will require less labor, be more convenient, rapid and economical and produce a stronger, tougher, more elastic and resilient product than is produced by any method heretofore known.

Another object is to provide a method whereby almost any article composed in whole or in part of rubber or similar material may be vulcanized or cured without the use of the usual molds, presses or other expensive machinery and equipment.

A further object of the invention is to provide a method whereby a metal medium is employed to effect the vulcanization or curing of rubber or similar substance and to further provide a simple, practical means whereby rubber may be given a dry cure and whereby the use of steam or hot water is entirely eliminated.

The above and other objects are accomplished as hereinafter set forth, it being understood that the invention is capable of various adaptations and that changes and alterations may be made or substitutions resorted to which come within the spirit of the invention or the scope of the claims hereunto appended.

In carrying out the invention, I employ any easily fusible metal or alloy such as those composed of bismuth, lead and tin mixed in the proper proportions to liquefy at a temperature slightly above the degree of heat necessary to effect vulcanization. The temperature of the metal is first raised to a degree sufficient to secure liquefaction. The article to be vulcanized is immersed in or surrounded by the molten metal which is then allowed to solidify, the metal being compounded as above set forth, the proportions of its constituents being arranged to insure solidification at a temperature above the degree of heat necessary to effect proper vul-

canization. The article is thus incased in a block of solid metal which will contract as the temperature thereof is lowered, thus compressing and compacting the article contained therein. The temperature of the metal is allowed to fall to a degree necessary to effect vulcanization at which point it is maintained until the article is vulcanized as desired. The metal is then cooled sufficient to coagulate the article contained therein, whereupon the metal is then quickly liquefied by raising its temperature and the vulcanized article is removed therefrom.

To more clearly illustrate the invention, I have furnished herewith a drawing which forms a part hereof and in which I have shown a way in which my method may be carried out with the use of simple instrumentalities and in which I have employed similar numerals of reference to indicate corresponding parts throughout the several views.

Figure 1 is a perspective view of a container showing a rubber heel and a rubber eraser positioned therein and also illustrating the manner in which molten metal may be poured thereon.

Fig. 2 is a vertical cross sectional view of said container taken approximately on line I I of Fig. 1, showing the same filled with metal and also showing said articles of rubber embedded therein.

As before set forth, any low fusible substance may be employed, preferably a substance composed of two or more metals intimately united. The ratio of the composition varying in accordance with the degree of heat at which fusibility is desired. The articles of rubber, or rubber composition, such as the heel 6 or the eraser 7 is preferably pre-formed and placed in a container 8, the metal 5 is subject to heat and thus liquefied, whereupon it is poured over and around the articles 6 and 7 as shown in Fig. 1. The metal is then allowed to solidify and the articles 6 and 7 are thus firmly embedded in solid metal. The heat is then applied and the metal is then kept at the vulcanizing temperature for the time required. The metal is then allowed to cool, thereby allowing the article being cured to completely coagulate. Then the metal is quickly liquefied and drawn off, or the articles are otherwise removed therefrom.

It is to be understood that the method

herein described is not confined to any particular article as the same may be used to vulcanize or cure any article composed in whole or in part of rubber or similar substance.

It is also to be understood that the invention is not confined to the use of the fusible metal herein described, but that any substance may be used which will liquefy and 10 solidify within the range of temperature necessary to acquire the desired results.

Having thus described my invention what I claim as new and desire to secure by Letters-Patent is:—

- 15 1. That process of vulcanizing rubber which comprises the following steps: heating a low fusible metallic substance to a degree sufficient to cause liquefaction; immersing the article to be vulcanized therein, cooling the metallic substance to a degree sufficient to produce solidification; subjecting the solidified mass to a vulcanizing heat for a sufficient period of time to insure vulcanization of the article incased therein;
- 20 25 cooling the solidified mass until the article contained therein has thoroughly coagulated, then quickly heating the mass to a

degree of heat sufficient to liquefy the same and removing the article therefrom.

2. That process of vulcanizing rubber 30 which comprises, placing the rubber in a molten mass of low fusible metal; cooling the mass to a degree of heat necessary to secure solidification; subjecting the solidified mass to a vulcanizing heat; then raising 35 the temperature of the mass sufficiently to secure liquefaction and removing the rubber therefrom.

3. That method of vulcanizing rubber which consists in providing a substance composed of low fusible metals intimately united in proportions adapted to produce a substance which will liquefy at a degree of heat above that which is necessary to effect vulcanization; producing a liquefaction of 40 said substance, bringing the article to be vulcanized in contact therewith, solidifying the substance and subjecting the whole to a vulcanizing heat; then producing a liquefaction of the substance and removing the 50 vulcanized article from contact therewith.

In testimony whereof I have hereunto set my hand.

FRANK O. E. STONE.
